UNITED STATES PATENT OFFICE

2,256,232

ELECTRIC CUTOUT WITH LIGHTNING PROTECTION

Ralph S. Bennett, Pittsfield, Mass., assignor to
General Electric Company, a corporation of
New York

Application January 13, 1939, Serial No. 250,787

9 Claims. (Cl. 200—115)

The present invention relates to electric cutouts and more particularly to improvements in protective equipment for fuse cutouts.

In some applications of fuse cutouts, troubles have been experienced from flashovers between the open circuited terminals or contacts of the cutout due to lightning surges. For example, in an installation where a fuse cutout is employed for transformer protection and is connected on the line side of the lightning arrester employed with the transformer, blowing of the fuse link leaves the cutout unprotected and tends to form at the line terminal of the cutout a reflecting point for lightning surges. As a result of this there may occur flashovers between the cutout terminals with danger of damage to, or even complete destruction of, the cutout casing or other insulating support. This danger exists also in cases where fuse cutouts are employed for line sectionalizing purposes and the circuit between the terminals is left open due to fuse operation.

It is a principal object of the present invention to provide, in a fuse cutout, simple and economical, yet reliable, protective means for preventing flashover and damage to the cutout due to lightning surges.

A more specific object of the invention is the provision of a unitary protective assembly, including a fuse and lightning protection means therefor, which may be substituted readily for an unprotected fuse assembly in an existing cutout installation without disturbance or alteration of the cutout support.

Other objects and the details of that which I consider to be novel and my invention will become apparent from the following description and the claims appended thereto, taken in conjunction with the accompanying drawing in which Fig. 1 shows an exemplary embodiment of the invention as applied to a fuse cutout of the enclosed type, and Figs. 2 and 3 are sectional views along the line 2—2 and 3—3 respectively of Fig. 1. Although the invention is illustrated and will be described herein as applied particularly to a cutout of the enclosed type, it is to be understood that the invention in its broader aspects is not limited to the details of the particular form of cutout disclosed and is applicable also to cutouts of the open type.

The cutout casing 10 shown on the drawing is of a form well known in the art and heretofore commonly employed in cutout installations incorporating only a single fuse holder or disconnect blade. This casing is constructed of porcelain or

other suitable insulation and is formed with electric creepage and gas barriers 11 and 12. Mounted in the casing are upper and lower terminal contacts 13 and 14 respectively of the form disclosed and claimed in my Patent 2,011,391, issued August 13, 1935, and assigned to the assignee of the present invention. Each of these contacts has two generally U-shaped resilient metallic elements 15 and 16, the bases of which are fastened together by means of one or more rivets 17. The spaced prongs of the inner element 16 are arranged to serve as contact fingers. The outer element 15 has two sets of prongs designated 18 and 19. Prongs 19 have lugs engaging recesses 20 in the inner faces of the side walls of casing 10 for supporting the contact assembly. Prongs 18 serve as backing strips for the contact fingers of element 16 and serve also as latching fingers in a manner which will become apparent herein after. The contact assembly includes also a base member 21 secured to elements 15 and 16 by rivets 17 and provided with a clamping member 22 for securing to the contact assembly a line conductor or lead inserted through an opening 23 in the side wall of the casing. The open front of the casing is closed by means of a door 25, of suitable insulation material, which is pivotally mounted at its lower end on removable studs 26 carried by projections at the lower end of the casing. The door has an eyelet handle 27 for manipulation thereof to and from closed position and has also barriers 28 arranged for co-operation with the barriers 11 and 12 of the casing.

On the inner face of door 25 is mounted a protective assembly including a fuse holder and expulsion gap interrupting device. The fuse holder is of a common form including an expulsion arcing tube 30, of insulation, having a contact sleeve 31 mounted on the upper end thereof. Within the fuse holder is disposed a fuse link, generally designated 32, the button-head upper terminal of which is secured in place by a removable cap 33, and the lower cable extension 34 of which fuse link projects out of the lower end of tube 30. The expulsion gap interrupting device has a double walled tube 35 of insulation upon the upper end of which is threaded a terminal cap 36. Within this tube is disposed a rod electrode 37 having a buttonhead terminal 38 secured in place by cap 36. A second electrode in the form of a metallic sleeve 39 is disposed within and adjacent the lower end of tube 35. The electrodes 37 and 39 are arranged in spaced relationship as illustrated, so as to provide an arcing gap within

the tube 35, and the sleeve form of electrode 39 provides for discharge of gases from the tube.

The upper ends of the fuse holder and the expulsion gap interrupter are secured together and electrically connected by means of a pin 40 in 5 screw-threaded engagement with sleeve 31 and cap 36, and the sleeve and cap are maintained in spaced relationship by means of a spacing nut 41. A rectangular clamp 42 is provided for securing together the lower ends of the fuse holder and 10 expulsion gap interrupter and maintaining these two devices in parallel juxtaposition. This clamp is secured to tube 35 and electrically connected with sleeve electrode 39 by means of screws 43. The two tubes are maintained in properly spaced 15 relationship by means of a notched sleeve 44 supported on a thumb-screw 45 extending between and supported by downwardly projecting spaced extensions 46 of clamp 42. One end of thumb-screw 45 is provided with a flange 47 for clamping 20 fuse link extension 34 to clamp 42.

The protective assembly just described is removably secured to the inner face of door 27 by quick detachable means in the form of resilient metallic clips 50 and 51. Clip 50 is secured to the door adjacent the upper end thereof by means of molded-in inserts 52 and has an opening 53 for engagement with the terminal cap 33 on the fuse holder. Clip 51 is U-shaped and is secured to the door adjacent the lower end thereof by a molded-in insert 55. The spaced resilient arms of clip 51 have knobs 56 engageable with sockets in clamp 42, as will be seen best from Fig. 3, to latch the lower end of the protective assembly to the door. The protective 25 assembly is readily attached to the door by first inserting cap 33 into opening 53 in upper clip 50, so as to latch the upper end of the assembly, and then pressing the lower end of the assembly 30 into latching engagement with lower clip 51. Thus the clips 50 and 51 serve to hold the assembly securely in position as shown.

When the door is closed, contact fingers 16 of the upper stationary contact assembly engage the sides of contact sleeve 31, as shown in Fig. 2, to effect electric connection with the upper end 35 of the protective assembly, and inwardly bent portions of prongs 18 engage the spaces between sleeve 31 and cap 36 to latch the upper end of the protective assembly in operative position. At the same time the contact fingers of element 16 and the prongs 18 of the lower stationary contact assembly engage clamp 42 to effect electric 40 connection with the lower end of the protective assembly. Thus the circuit between the stationary contacts is completed through fuse link 32.

In case the fuse link blows upon excess current, the resultant open circuit condition between the stationary contacts would render the cutout subject to flashover between the stationary contacts due to lightning surges were it not for the provision of the expulsion gap interrupter. However, with the arrangement of the present invention, the expulsion gap interrupter provides an impulse current discharge path between the stationary contacts and the terminals of the protective assembly. The spacing between the electrodes 37 and 39 is so arranged 45 that breakdown of the gap therebetween will occur before flashover between the stationary contacts or between external conductive parts of the protective assembly. Thus the cutout is at all times protected from damage due to flash-

over when the circuit is open between its contacts by reason of fuse operation.

With the arrangement described it is not essential to provide a gap in series with the expulsion gap interrupter since, under normal operation, the fuse link is in the circuit so that the voltage across the terminals of the gap is very low. Thus there is not the danger, present in some expulsion gap interrupter installations, of creepage between the gap electrodes with resultant progressive carbonization of the tube of the interrupter.

One of the important features of the arrangement in accordance with my present invention is that the tubes of the fuse and the expulsion gap interrupter are supported in alignment parallel to the rear face of the door. By reason of this, the protective assembly is adapted to fit into standard cutout casings originally designed for accommodation only of a single fuse assembly. Thus it is possible to replace an unprotected single fuse assembly with a new cover having attached thereto the protective assembly hereinbefore described. Increased protection may thereby be secured with little additional expense since dismounting or alteration of the cutout casing or other support is not required.

What I claim as new and desire to secure by Letters Patent of the United States is:

1. In an electric cutout, the combination with an insulating support having a pair of spaced line terminal contacts mounted thereon, and a fuse assembly carried by said support and including a fuse link electrically connected between said contacts; of an expulsion gap interrupter including an expulsion tube having spaced electrodes providing a discharge gap in the tube and having spaced terminals for said electrodes, means supporting said interrupter with its said terminals in electric association respectively with said contacts, and means including said terminals and electrodes operative to provide a lightning impulse discharge path interconnecting said contacts by way of said gap and tube when the circuit between the contacts is open due to rupture of said fuse link.

2. In an electric cutout, the combination with 50 an insulating support having a pair of spaced line terminal contacts mounted thereon, of an electric protective assembly detachably mounted on said support and comprising a pair of spaced terminals for connection respectively with said pair of contacts, a fuse electrically connected between said terminals, an expulsion gap interrupter including an expulsion tube having spaced electrodes providing a discharge gap in the tube, common supporting means for said fuse and interrupter, and means cooperative with said electrodes to provide a lightning impulse discharge path interconnecting said terminals by way of said gap and expulsion tube when the circuit between the terminals is open 55 due to operation of said fuse.

3. In an electric cutout, the combination with an insulating support having a pair of spaced line terminal contacts mounted thereon, of an electric protective assembly comprising a tubular fuse holder having a fuse link therein, an expulsion gap interrupter including an expulsion tube having spaced electrodes providing a discharge gap in the tube, means common to said fuse holder and expulsion tube for detachably mounting the assembly on said insulating support, spaced ter-

minals for said fuse link arranged for connection respectively with said contacts, and means connecting said electrodes respectively with said terminals.

4. In an electric cutout, the combination with an insulating casing having a pair of spaced line terminal contacts therein and a door for the casing, of an electric protective assembly supported on the inner side of said door and comprising spaced terminals for the assembly arranged for connection respectively with said contacts, a fuse electrically connected between said assembly terminals, an expulsion gap interrupter including an expulsion tube having spaced electrodes providing a discharge gap in the tube and having spaced terminals for said electrodes, which said electrode terminals are electrically associated respectively with said assembly terminals, and means including said electrode terminals and electrodes operative to provide a lightning impulse discharge path interconnecting said assembly terminals by way of said gap and expulsion tube when the circuit between the assembly terminals is open due to operation of said fuse.

5. An electric protective unit comprising in combination, a door adapted to close an open side of an electric cutout or like casing, a fuse, a pair of spaced terminals for said fuse arranged for connection respectively with a pair of spaced contacts in a cutout or like casing, an expulsion gap interrupter including an expulsion tube having spaced electrodes providing an arcing gap in the tube, means supporting said fuse and interrupter on the inner side of said door, and means cooperative with said electrodes to provide a lightning impulse discharge path interconnecting said terminals by way of said gap and expulsion tube.

6. An electric protective unit comprising in combination, a door adapted to close an open side of an electric cutout or like casing, a fuse, an expulsion gap interrupter including an expulsion tube having spaced electrodes providing an arcing gap in the tube, means common to said fuse and interrupter detachably supporting the fuse and interrupter on the inner side of said door, a pair of spaced terminals for engagement respectively with a pair of spaced contacts in a cutout or like casing, means connecting said fuse between said terminals, and means connecting said electrodes respectively with said terminals.

7. An electric protective unit comprising in combination, a door adapted to close an open side of an electric cutout or like casing, a tubular fuse holder having a fuse link therein, an expulsion gap interrupter including an expulsion tube having spaced electrodes providing an arcing gap in the tube, means clamping said holder and tube in non-coaxial substantially parallel juxtaposition to form a unitary assembly, means detachably securing said assembly to the inner side of said door, a pair of spaced terminals for said assembly arranged respectively to engage a pair of spaced contacts in a cutout or like casing, means connecting said fuse link between said terminals, and means connecting said electrodes respectively with said terminals.

8. An electric protective unit comprising in combination, a door adapted to close the open front of an electric cutout or like casing, a tubular fuse holder having a fuse link therein, an expulsion gap interrupter including an expulsion tube having spaced electrodes providing an arcing gap in the tube, spaced terminals for engagement respectively with spaced contacts in a cutout or like casing, means connecting said fuse link between said terminals, means connecting said electrodes respectively with said terminals, and means supporting said fuse holder and expulsion tube in non-coaxial substantially parallel extending juxtaposition on the inner side of said door with the axes of the holder and tube substantially in alignment in a plane perpendicular to the rear face of the door.

9. An electric protective unit comprising in combination, a first circuit interrupting device including a tubular insulating holder and conductive means therein operable to interrupt current flow in the holder, a second circuit interrupting device structurally separate and distinct from said first device and including an expulsion tube having spaced electrodes providing a surge gap in the tube, means common to said devices for supporting the same removably on an insulating support, and a pair of spaced terminals designed for engagement respectively with spaced contacts on such insulating support, which said terminals are electrically connected respectively with the opposite ends of said conductive means and also are electrically connected each with a respective one of said electrodes.

RALPH S. BENNETT.
